UNITED STATES PATENT OFFICE.

WILLIAM F. MACLACHLAN, OF CHICAGO, ILLINOIS.

ANTITHUMB-SUCKING DEVICE.

Application filed June 2, 1924. Serial No. 717,314.

This invention relates to improvements in anti-thumb sucking devices and consists of the matters hereinafter described and more particularly pointed out in the appended 5 claims.

The object of the invention is to provide a device which may be readily attached to the thumb or finger most generally used in the habit of thumb or finger sucking, which 10 device will discourage and will positively break such a habit,—and this without interfering in any way with the normal use of said thumb or finger.

A further object of the invention is to provide such a device, which may be readily applied to the offending thumb or finger, and includes a flexible attaching device adapted to be easily and quickly secured to and removed from the wrist.

20 These objects of the invention as well as the many advantages thereof will more fully appear as I proceed with my specification.

In the drawings:—

Fig. 1 is a perspective view of my improved anti-thumb sucker as it appears when applied to the offending thumb of a child's hand.

Fig. 2 is a perspective view of the device on an enlarged scale.

30 Fig. 3 is a top plan view of the device.

Fig. 4 is a longitudinal section through a contractile coiled spring embodied in my improved device.

Referring now to that embodiment of the 35 invention illustrated in the accompanying drawing:—The device consists of a thimble like guard adapted to be applied to the thumb or finger and to extend up to the first joint thereof, and a flexible attaching member in the form of a fine chain which is connected at one end to the guard, the other end of the chain being intended to be wrapped one or more turns about the wrist to hold the guard upon said thumb or finger.

45 5 indicates the body of a thimble like guard preferably made of silver or other suitable material and which is of a size adapted to receive or be slipped over the offending thumb or finger, and of a length so as to terminate at the first joint thereof. The outer end of said guard is defined by two transversely curved bands 6—6 which are connected at their ends to the body of the guard and intersect at the axis of the said body to provide a plurality of substantially triangular ventilation openings 7—7 between

said bands, there being another ventilation opening 8 provided at the intersection of said bands. Secured to the guard body, at the ends of the bands 6—6 is a circumferential projection in the form of a radially extending flat ring 9.

The open end of the body of said thimble like guard, has a bead 10 and between said bead and said radial flat ring 9 is provided a plurality of longitudinally extending slots 11—11, which are arranged in planes between the planes of the transversely curved end bands 6. Said slots not only provide additional ventilation openings in the guard body but also provide a limited flexibility in said body. Secured to the body 5 adjacent the bead 10 are diametrically opposite, radially extending, apertured ears 12—12 to which the ends of a length of fine link chain is secured to provide a loop 13. A cross member 14 also made of a fine link chain is attached at its ends to the chain of the loop 13 as shown in Fig. 2.

15 indicates a flexible member of a predetermined length which is attached at one end to the loop 13 as will later appear and is adapted to be wound about the wrist to secure the thimble like guard upon the thumb. Said flexible member is in the form 80 of a fine link chain with an eye 16 at one end, through which the loop 13 freely passes and with a spring snap ring 17 at the other end, similar to those used on watch chains to connect one of said chains to the bow of 85 a watch. Interposed in the chain 15 preferably near the ring 16 is an elastic member in the form of a contractile spring 18 of small diameter. Inside the spring is a flexible member 18^a in the form of a small chain 90 having a predetermined amount of slack therein and being connected at its ends to the ends of the spring 18. This spring 18 and chain 18^a permits the chain 15 to expand or stretch to limited predetermined length under the action of the bending of the thumb when the guard is upon the thumb, which length is not enough to allow the thimble like guard to be slipped off the thumb.

105 Preferably but not necessarily so, a portion of the body of the guard 5 between the bead 10 and flat radial ring 9 is roughened as by the knurling 19 as shown in Fig. 2.

To apply the device in position, the guard body is slipped over the thumb with the cross chain 14 engaging the under part of the thumb and with the ears 12—12 on op-

posite sides thereof. The free end of the chain 15 is then drawn over the back of the hand and is wrapped one or two turns about the wrist and the spring snap ring 17 is hooked into one of the links of said chain as shown in Fig. 1. This securely attaches the device to the thumb or finger so that it cannot be removed by the child.

As the thumbs and fingers of children of 10 that age who practice thumb sucking are supple and limber, the cross chain 14 connected to the loop 13 prevents the device from being slipped off the thumb by the child even though the thumb is bent back- 15 wardly because it holds the loop in close engagement with the thumb.

When the thumb or finger with the device thereon, is inserted into the mouth, the flat radial ring 9 comes in contact with the roof 20 of the mouth and with the tongue producing discomfort, but no pain, and prevents the actual contact between the thumb and mouth parts which is necessary in order to produce the fancied satisfaction due to the 25 sucking upon the thumb or finger. When the thumb is withdrawn from the mouth, even though moist or wet with saliva, it will soon dry out because of the ventilation through the openings provided therefor.

30 The spring 18 with the chain length 18^a therein permits the thumb to be bent in the usual normal movement of the thumb so that no discomfort results from the wearing 35 of the device. Furthermore, the end of the thumb is so enclosed as to prevent the biting of the nail thereof, which in many instances is a habit which accompanies thumb sucking in children of more mature age.

The device will discourage the child from 40 putting the thumb or finger in the mouth while awake, because of the realization of the impossibility of satisfaction when the device is upon the thumb or finger, it being borne in mind that only one thumb or a 45 certain finger is used in this practice, and the child will not get the satisfaction desired by the use of another or different thumb or finger. Should the child in its sleep, due to

habit alone insert the thumb or finger in its mouth, it will be shortly withdrawn because 50 it receives no satisfaction therefrom, not only because direct contact between the thumb and mouth parts cannot be made but also because of the strangeness of the feeling of the device while the thumb or finger 55 is in the mouth.

The device is sanitary and may be readily sterilized in any convenient manner. It produces no discomfort when in place and cannot be removed by the child.

While in describing my invention, I have referred to certain details of construction and arrangement of parts, I do not wish to be limited thereto except as may be pointed out in the appended claims.

I claim as my invention:—

1. An anti-thumb sucking device comprising a substantially rigid thimble-like member adapted for application to the thumb or finger, said thimble-like member having 70 openings in one end thereof and being provided adjacent said end with a rigid radially projecting member disposed annularly to the said member, a flexible loop connected at its ends to said thimble-like member, and a flexible member connected to said loop and adapted to be wrapped around the wrist to secure said thimble-like member upon a thumb or finger.

2. An anti-thumb sucking device comprising a substantially rigid thimble-like member adapted for application to the thumb or finger, said thimble-like member having openings in one end thereof and being provided adjacent said end with a rigid radially projecting member disposed annularly to the said member, a flexible loop connected at its ends to said thimble-like member, a cross chain connecting the sides of said loop, and a second chain having an eye at one end 90 operatively connected to said loop so that the loop may slide therethrough.

In testimony that I claim the foregoing as my invention, I affix my signature this 29th day of May, 1924.

WILLIAM F. MACLACHLAN.
